2 SHEETS—SHEET 2.

UNITED STATES PATENT OFFICE.

SARAH E. AVERY, OF COLUMBIA, SOUTH CAROLINA.

FOLDING SEWING-MACHINE.

1,136,921.

Specification of Letters Patent. Patented Apr. 27, 1915.

Application filed June 18, 1914. Serial No. 845,964.

To all whom it may concern:

Be it known that I, SARAH E. AVERY, citizen of the United States, residing at Columbia, in the county of Richland and State of 5 South Carolina, have invented certain new and useful Improvements in Folding Sewing-Machines, of which the following is a specification.

This invention relates to an improvement 10 in folding sewing machines.

The primary object of the invention is to provide a sewing machine which may be folded to occupy a comparatively small space and in which the bed-plate and the 15 arm which supports the needle actuating mechanism may be housed within a cabinet and the driving mechanism folded on the cabinet and maintained in its folded position by the supporting table for the bed- 20 plate.

A further object of the invention is to provide a construction in which the various parts may be readily folded and which when unfolded for use will operate as effect- 25 ually as the usual sewing machine construction.

A still further object of the invention is to provide a mechanism of this character in which all of the mechanical parts will be 30 effectually housed, whereby the device may be conveniently transported.

For a full understanding of the invention, reference is to be had to the following description and accompanying drawings, in 35 which:—

Figure 1 is a front elevation of the machine set up for use; Fig. 2 is a front elevation partly in section showing the device folded; Fig. 3 is a section on the line 3—3 40 of Fig. 2; Fig. 4 is a section on the line 4—4 of Fig. 1.

Corresponding and like parts are referred to in the following description and indicated in all the views of the accompanying drawings 45 by the same reference characters.

In the drawings, 10 designates a cabinet which may be of any suitable design, but which preferably consists of the base portion 11 which supports a plurality of draw- 50 ers 12. The cabinet is formed with a compartment 13, a lid 14 being hingedly connected to the cabinet and forming a closure for this compartment. The ledge with which the cover 14 contacts is formed with 55 an extension 15 at one side of the cabinet and to this extension is hingedly connected

a table 16. This table is supported by a plurality of braces 17, there being a brace 17 hingedly mounted adjacent each edge of the cabinet below the extension 15. These 60 braces 17 are disposed to fold on the cabinet and when the machine is set up for use they effectually support the table 16. The table 16 is provided with an opening 17' which receives the flange 18 of the bed-plate 19 on 65 which the arm 20 which houses the needle actuating mechanism is mounted. This needle actuating mechanism may be of any suitable construction.

The bed-plate 19 is hingedly mounted at 70 one side of the top of the cabinet, and the plate may thus be folded to dispose the arm 20 within the cabinet, the edge 22 of the plate resting upon the flange 23. It will thus be seen that the needle actuating 75 mechanism may be folded within the cabinet and the lid 14 closed.

A sheave 24 is mounted upon the side 25 of the cabinet, a belt 26 passing over said sheave and the sheave 27 of the needle actuating mechanism which is supported by the arm 20 mounted on the bed-plate. The crank wheel 28 is connected with the sheave 24 and a connecting rod 29 is connected to the crank 30 of said wheel. A plurality of brackets 80 31 and 32 are mounted in spaced relation on the wall 25 of the cabinet adjacent its base. These brackets are provided with spaced ears 33. A treadle 34 is hingedly supported by the bracket 32, said treadle being formed 85 with an extension 35 which is disposed between the ears 33 of the bracket 32, a pin 36 passing through said ears and said extension. An arm 37 is pivotally supported between the ears 33 of the bracket 31, said arm 90 being formed with an extension 38 disposed at right angles to its body portion and provided at the point where it is bent with a foot 39.

The treadle is formed with a trunnion 40 100 mounted upon the extension 38 of the arm 37, the terminal of said extension being provided with a foot 42. Thus the treadle is supported by the feet 39 and 42 when the machine is set up for use. The rod 29 is 105 connected to the extension 43 of the treadle by a universal joint, whereby the treadle will actuate the crank wheel 28.

When it is desired to fold the machine, the bed-plate 19 is lifted and inverted, the 110 edge of the plate resting upon the flange 23. The lid 14 is then closed. The braces

17 are then folded beneath the extension 15 and the table 16 is lowered. The treadle is swung upon its pivotal support and the same, together with the arm 37 and its extension 38, is brought in contact with the wall 25 of the cabinet.

10 A plurality of hooks 44 are secured to the wall 25 of the casing, the terminals of said hooks being inserted within eyes 45 arranged on the under face of the table 16, thereby maintaining the table in spaced parallel relation to the wall 25 and housing the driving mechanism. It will, therefore, be noted that the entire mechanism of the machine is thus 15 effectually housed and occupies a comparatively small space. It will also be seen that the entire structure is such as may be easily and economically manufactured, and that the various parts may be readily assembled.

20 What I claim is:

1. A folding sewing machine comprising a cabinet provided with a compartment, a table hingedly supported adjacent one edge of said compartment, a base plate hingedly supported by said edge, a needle operating mechanism arranged on said base plate, the base plate being movable to one position seated upon the table to support the needle operating mechanism in operative position and to another position to dispose the needle operating mechanism within the compartment, a driving mechanism having an operative connection with the needle operating mechanism, said driving mechanism being 25 hingedly supported on the cabinet, said table when folded being disposed parallel with the side wall of the cabinet, and the driving mechanism being housed between the table and the cabinet.

30 2. A folding sewing machine comprising a cabinet, said cabinet being formed with an extension, a table hingedly mounted on said extension and disposed to assume a position parallel with the adjacent side wall 45 of the cabinet, a base-plate hingedly supported on the cabinet and movable to operative position to rest upon the table, a needle operating mechanism mounted on said base-plate, said cabinet being provided with a 50 compartment disposed to receive the base-plate and needle operating mechanism, and a driving mechanism for the needle operating mechanism hingedly mounted on the cabinet, said table, when folded, being disposed parallel with the adjacent wall of the cabinet, the driving mechanism being disposed between the table and the cabinet, and means for maintaining the table in spaced 55 relation with respect to the cabinet.

60 3. A sewing machine comprising a cabinet, a table hingedly supported by the cabinet, means for supporting said table in alinement with the top of the cabinet, a base-plate supported by the cabinet, a needle 65 operating mechanism arranged on said base-

plate, the base plate being movable to one position seated upon the table to support the needle operating mechanism in operative position and to another position to dispose the needle operating mechanism within the 70 cabinet, a sheave rotatably supported by the cabinet, a crank disk secured to said sheave, a lever having an operative connection with said crank disk, a treadle hingedly mounted on the cabinet and disposed to actuate said lever to rotate the crank disk, and means for maintaining the table in spaced parallel relation with the adjacent side of the cabinet, the driving mechanism being disposed between said table and cabinet. 75

4. A folding sewing machine comprising a cabinet, said cabinet being formed at its top with an extension, a table hingedly mounted on said extension, means for supporting said table in alinement with the top of the cabinet, a base-plate hingedly mounted on the cabinet, a needle operating mechanism mounted on said base-plate, the base plate being movable to one position seated upon the table to support the needle operating mechanism in operative position and to another position to dispose the needle operating mechanism within the cabinet, a driving mechanism supported by the cabinet and having an operative connection with the needle operating mechanism, and means for supporting said table parallel with one wall of the cabinet. 85

5. A folding sewing machine comprising a cabinet, a table hingedly supported at the upper end of said cabinet, a needle actuating mechanism hingedly supported by the cabinet, said mechanism being movable to operative position to rest upon the table and to inoperative position within the cabinet, means for supporting said table in alinement with the top of the cabinet, a driving mechanism for the needle actuating mechanism hingedly mounted on the cabinet, and means for supporting said table parallel with one of the side walls of the cabinet, the driving mechanism being disposed between the table and the cabinet. 105

6. A folding sewing machine including a cabinet a table swingingly connected to the cabinet, a needle actuating mechanism swingingly supported upon the cabinet, said mechanism being movable to operative position to rest upon the table and to inoperative position within the cabinet, means for operatively supporting the table, and a driving mechanism for the needle actuating mechanism swingingly connected to one side of the cabinet and movable to position to rest against the said side between the table and the cabinet. 115

7. A folding sewing machine including a cabinet, a table swingingly connected to the cabinet, a needle actuating mechanism 120

swingingly supported by the cabinet, said mechanism being movable to operative position to rest upon the table and to inoperative position within the cabinet, means for supporting the table in operative position, a treadle swingingly connected to the cabinet, and a universal connection between the treadle and the needle actuating mechanism whereby the treadle may be moved to rest 10 against one side of the cabinet housed by said table.

8. A folding sewing machine comprising a cabinet, a table swingingly connected to the cabinet, a needle actuating mechanism 15 swingingly connected to the cabinet, said mechanism being movable to operative position to rest upon the table and to inoperative position within the cabinet, means for

supporting the table in operative position, a treadle swingingly connected to the cabinet, 20 an arm swingingly connected to the cabinet adjacent the treadle, the said arm being formed with an extension operatively supporting one end of the treadle, and means operatively connecting the treadle with said 25 needle actuating mechanism whereby the treadle, the said arm and its extension may be swung to rest against one side of the cabinet housed by said table.

In testimony whereof I affix my signature 30 in presence of two witnesses.
